UNITED STATES PATENT OFFICE.

THOMAS O. SCOTT AND GEORGE W. STYER, OF BUFFALO, NEW YORK.

COLLAPSIBLE SHIPPING-CRATE

No. 915,704.

Specification of Letters Patent. Patented March 16, 1909.

Application filed March 4, 1908. Serial No. 419,179.

To all whom it may concern:

Be it known that we, THOMAS O. SCOTT and GEORGE W. STYER, citizens of the United States of America, residing at Buffalo, in the 5 county of Erie and State of New York, have invented certain new and useful Improvements in Collapsible Shipping-Crates, of which the following is a specification.

The invention relates in general to an improvement in collapsible or knockdown packing crates and specifically to one adapted, after the original contents thereof has been removed, to be folded in compact form and returned to the shipping point in 15 collapsed condition for repacking and shipping, and to one provided with means for securely holding in desired relation the several sections of the crate when filled and in shipment.

20 The main object of the invention is to provide a crate of the kind described which shall comprise means for effectively locking the contiguous edges thereof in rigid operative relation to withstand the customary 25 rough handling in shipment, said means being simple in construction and operation and, when performing its function lying practically within the plane of the surface of the crate.

30 Another object is to so proportion and form the several coöperating parts of the crate that when it is in collapsed form they shall lie closely contiguous and compact and eliminate as far as practicable liability of 35 injury to the crate when being shipped in such form.

In the drawings, Figure 1 is a perspective of our improved crate, one end thereof being shown in dotted lines in partially folded position. Fig. 2 is a broken perspective illustrating the locking means, the normally contiguous edges of the crate being shown in unlocked position. Fig. 3 is a broken perspective showing the locking means in operative position, and Fig. 4 is a front view of the crate in collapsed condition.

Referring now to the drawings, wherein like reference numerals refer to like parts throughout the several views, 1 and 2 40 note the two duplicate ends of the crate, 3 and 4 the back and front and 5 and 6 the bottom and lid thereof respectively. The ends and the front and back are pivotally connected to the bottom through the medium of hinge connections 7 at the upper edge of an upwardly-extending flange 8

formed on the four sides of said bottom integral therewith, that portion of said flange extending along the front and back edge of the bottom being of greater width than that portion extending along the side edges thereof, for a purpose to be hereinafter explained.

• Formed integral with ends 1 and 2, on their front and back edges and extending the entire length thereof, are outwardly-extending locking flanges 9 adapted to engage and fit within inwardly-extending flanges 10 formed on the ends of the back and front sections of the crate and extending the full width thereof. Flanges 9 are formed with notches 11, designed, when flanges 9 and 10 are in operative engagement, to align with notches 12 formed in the edges of the front and back section. 75

Passing through overturned portions of the end sections forming the beads of the tops thereof and adapted for partial rotation therein, are locking rods 13 bent, at their point of egress from said overturned portion, for a short distance of their length in a lateral direction and then in parallel relation to the body portion of the rod to form lugs 14, preferably of resilient material and designed to be sprung into the aligned notches when performing their function. 80

The lid 6, which as shown in Fig. 1, is hinged at 15 to the back of the crate, is provided with a downwardly-disposed flange 16 adapted, when said lid is closed upon the 90 locked sides of the crate to snugly embrace and fit the top edge thereof, said flange being of sufficient width to cover, when in closed position on the locked box sides, the operatively-positioned locking rods 13 and prevent accidental displacement thereof, the usual hasp being provided as supplementary securing means if desired. 95

In the event that it is desirable to inspect the contents of the crate without opening the 100 same, one or more sides may be provided with an inspection opening, covered with any suitable transparent material 17, while handles 18 may be added if desired.

In assembling the crate for filling, the 105 ends, front and back are swung to upright position, flanges 9 passed into flanges 10 and the locking rods rotated downwardly until lugs 14 can be sprung into aligned notches 11 and 12, the resilient quality of said rods effectively retaining them in said notches until manually released and effectually preventing 110

accidental disengagement of the ends of the crate from the back and front thereof, that part of said locking rods between the portions passing through the beads of the end sections and the lugs 14 lying, when said lugs are in notches 11 and 12, closely contiguous the inner surface of flanges 10 and spaced slightly from the outer edges thereof, as shown in Fig. 3, accidental contact of the locking rods, and consequent liability of disassembling the crate at inopportune times in handling the crate, being thus further provided against.

In arranging the crate for shipping in collapsed form, lugs 14 are sprung out of engagement with notches 11 and 12, either end 1 or 2 folded down upon the bottom, the other end folded upon the first end and the front folded upon the latter, the flange connecting said front being of such height as to snugly accommodate below its top edge the ends and front of the crate when folded as described. The back is then folded forward upon the folded front and the lid folded back 25 upon the back 3.

The above details embody the preferred form of our invention but we do not wish to be limited thereto and contemplate employing any modifications thereof that may fall 30 within the scope of our invention, and especially of using any material suitable for constructing the crate.

From the foregoing it will be readily seen that we have provided a crate which, due to 35 the construction and relation of the several parts, is as strong and durable as though formed with permanent joints, which can be readily and conveniently assembled in crate form and which is capable of being quickly 40 folded into small, compact form for return shipment.

Having thus described the invention what is claimed as new, is:—

1. A collapsible box including a cover, 45 side and end walls, the end walls being formed with outwardly projecting edge flanges, the side walls being formed with edge flanges of U-shape to receive the edge flanges of the end walls, and catches carried 50 by the end walls to engage the connected flanges, the cover fitting the upper ends of the side and end walls and locking the catches against disengagement.

2. A collapsible box including a cover, 55 side and end walls, the end walls being formed with outwardly projecting edge flanges, the side walls being formed with edge flanges of U-shape to receive the edge flanges of the end walls, the flanges of the 60 side and end walls being formed with registering notches, and catches carried by the end walls to engage in said notches, the cover fitting the upper ends of the side and

end walls and locking the catches against disengagement.

3. A collapsible box including interlocking side and end walls and locking rods rotatably carried by and extending throughout the width of the end walls, said rods projecting beyond the side edges of the end 70 walls and formed to provide catches, the side and end walls being formed with notches adapted to register when said parts are interlocked to receive the catches, whereby both side walls are secured to the particular 75 end wall by the operation of a single locking rod.

4. A collapsible box including side and end walls, the end edges of the side walls being formed in return bends to provide housings, 80 the side edges of the end walls being formed with outwardly-extending flanges adapted to fit within the housings of the side walls when the parts are in box-forming positions, each housing and coöperating flange being 85 formed with notches adapted to register, and a single locking rod having end catches adapted to engage the registering notches between one end wall and both side walls in a single movement of the rod.

5. A collapsible crate including side and end walls, the end edges of the side walls being formed in return bends to provide housings, the side edges of the end walls being formed with outwardly-extending flanges 95 adapted to fit within the housings of the side walls when the parts are in box-forming positions, each housing and coöperating flange being formed with notches adapted to register, the housings of the side walls and 100 the flanges of the end walls projecting outwardly beyond the end walls, locking rods mounted in the end walls, catches carried by the locking rods and adapted to engage the registering notches, said catches bearing 105 against the inner sides of the housings when in locking position, whereby said housings protect the catches against accidental displacement.

6. A collapsible box including side and end 110 walls, the end walls being formed with outwardly projecting edge flanges, the side walls being formed with edge flanges of U-shape to receive the edge flanges of the end walls, the flanges of the side and end walls 115 being formed with registering notches, rods revolvably mounted in the end walls and terminally formed to provide catches to engage the notches in the flanges.

In testimony whereof we affix our signatures in presence of two witnesses.

THOMAS O. SCOTT.
GEORGE W. STYER.
